UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,274,655.

Specification of Letters Patent.

Patented Aug. 6, 1918.

Application filed May 4, 1912. Serial No. 695,056.

To all whom it may concern:

Be it known that I, WALTER WRIGHT, a citizen of the United States, residing in New York city, in the county of New York and State of New York, have invented certain new and useful Improvements in Combined Type-Writing and Computing Machines, of which the following is a specification.

This invention relates to computing mechanisms, particularly those combined with typewriting machines, of the class in which the dial or computing wheels or members are rotated or advanced one after another by means of a common actuator, as for instance a master-wheel; and in which a relative step-by-step movement is effected between the master-wheel and the computing wheels.

The invention is an improvement on my application, Serial No. 59,002, filed November 1, 1915, which is a division of my patent, No. 1,160,102, dated November 9, 1915.

Owing to the inertia of the computing wheels and of the connections from the keys to the wheels, as well as to the inertia of the tens-carrying or carry-over trains, it has been found in practice that the labor of depressing the computing keys to drive the wheels is excessive. I have disclosed in said application means to relieve the operative of part of this labor by providing power means, separate from the keys, to drive the tens-carrying trains. In the present case, I use a continuously running electric motor for this purpose, and make other changes in construction and mode of operation, whereby a very smoothly operated machine is produced. Owing to the consequent lightening of the key touch, the speed of manipulation of the machine tends to increase; and since the time within which the electric motor can turn the computing wheels is usually limited to the minute interval in which the typewriter carriage is at rest between type impressions, there is a tendency for the speed of the typist to outrun the speed of the machine. One of the objects of the present invention is to reduce or overcome this tendency, without, however, making the key touch unduly heavy.

Accordingly, I connect the master-wheel to the numeral keys of the typewriter, to be driven directly thereby; and I provide also an electric motor or suitable source of power for operating the carry-over devices. Thus

the work is divided between the keys and the motor. The resistance of the keys, due to the necessity of rotating the master-wheel, is not appreciable or objectionable; moreover the key never has to drive more than a single computing wheel of the series, inasmuch as the driving of any other computing wheels at the tens-carrying operation is taken care of by the power mechanism. The rotation of the computing wheel in each instance is completed during the down stroke of the typewriter key, so that there is no likelihood of the manipulation of the keys outrunning the speed of the mechanism. Thus I have produced a machine which meets the exacting requirements of speed and accuracy of a combined typewriting and computing mechanism.

In the preferred form of the invention, the key-driven connections are practically all rotating parts, and extremely light. Moreover, they always rotate in the same direction; and the parts gather speed one after another, so that there is no great inertia to be suddenly overcome.

In the preferred form of the invention, a totalizer moves with a typewriter carriage, while the master-wheel does not travel. This master wheel is preferably driven by the keys in such a way that during the operation of any numeral key, the said master wheel is either being positively driven or else positively locked by the key, so that not only is the throw of a computing wheel direct, but overthrow becomes impossible.

Each computing wheel is preferably arranged to be always held alined by a detent unless it is positively under the control of the master wheel. Each computing wheel may be constantly in mesh with the carry-over wheel arranged to drive it, and the detents may be arranged to operate on these carry-over wheels. The detent governing the active computing wheel is arranged to release said computing wheel during the time the master-wheel is turned.

Other features and advantages will hereinafter appear.

In the accompanying drawings, Figure 1 represents a diagrammatic side view of an Underwood typewriter including my invention.

Fig. 2 is a sectional view of the computing mechanism of the same on the line *a—a* of Fig. 3.

Fig. 3 is a fragmentary front view of the computing mechanism.

Figs. 4 and 5 show the relation of the master-wheel to the computing mechanism.

5 Fig. 6 shows the power-driven assisting member for the carry-over mechanism.

Fig. 7 is a perspective view of a cam on a locking and driving unit operated by a numeral key.

10 Fig. 8 shows the relation of the locking and driving units to the totalizer carriage lock operating shaft.

Numeral keys 1 and alphabet keys 2 depress levers 3 to swing type bars 4 through bell cranks 5 upwardly and rearwardly to cause types 6 to strike a platen 7 in a carriage 8. Said carriage is drawn forward in letter-feeding direction by means of a spring 9 and is controlled in said letter-feeding by means of an escapement wheel 10 carrying a pinion 11 working in a rack 12 on said carriage, said escapement wheel being controlled by dogs 13 moved from heels 14 on the type bars through a universal member 15.

As said carriage 8 moves, it carries along with it by means of an arm 16 a totalizer 17 on a totalizer carriage 18, which carriage 18 rides on the rolls 19 and causes wheels 20 to be engaged *seriatim* by a master wheel 21. Said master wheel is turned from the numeral keys in a manner to be presently described, and said wheels 20 turn dial wheels 22 through intermediate gears 23 and 24.

35 The master wheel is turned by the depression of any numeral key 1 by means of an adjustable link 25 pivotally attached to a partly toothed segment 26, which segment turns a combined lock and driving unit 27 alternately locking and driving an intermediate shaft 28 geared to said master wheel 21. Said unit 27 is loose on shaft 27^a, and comprises the parts between the cam 35 and the cam 45 (See Fig. 8).

45 Said locking and driving unit 27 is normally held locked against rotation by means of its teeth 29 and 30, which bear against a flat portion of said partly toothed segment 26. As a numeral key 1 is depressed drawing down said segment, the tooth 29 on said locking and driving unit is arranged to be struck by a tooth 31 on said segment, so that the remaining teeth 32 of the locking and driving unit will successively mesh with the teeth 33 of said segment and positively rotate the segment until a broad flat surface 34 at the upper end of said segment is struck by the tooth 29 of the locking and driving unit in its rotation, and said unit is positively arrested thereby. The numeral key may then continue to descend idly as far as the computing mechanism is concerned.

The intermediate shaft 28 is held under positive control during the entire operation of a numeral key. For this purpose it is first

locked when the locking and driving unit begins to turn. The locking is accomplished by a cam 35 forming part of said unit, which cam moves opposite a cam surface 36 fast on the intermediate shaft 28, and locks said shaft 28 against rotation. Later said unit positively turns said shaft 28. To do this turning it unlocks said shaft by bringing a broken away portion 87 of said cam 35 opposite the cam surface 36 of said shaft 28, unlocking said shaft, and simultaneously teeth 37, forming part of said locking and driving unit, turn said intermediate shaft 28 by meshing with teeth 38, forming part of a gear wheel fast on shaft 28, and positively turn said shaft till the last tooth 37 has turned said shaft 28. Then said shaft 28 is again locked by an unbroken part of the cam 35 which again locks said shaft 28 against further rotation. In so turning shaft 28, the master wheel 21 is turned with it. It will be observed that the locking and driving unit makes a complete revolution at each operation of a numeral key, and that the extent to which the master wheel is turned depends entirely on the number of teeth 37 on the unit. The unit shown in Figs. 2 and 8 is the one for the "9" key and so has nine teeth.

As the numeral key 1 is released, the segment 26 rises idly, for the tooth 30 of the locking and driving unit will fail to mesh with the first tooth 39 of said segment, owing to a slight friction of the parts. The unit is then locked by said tooth 30 riding on a smooth surface 40 on said segment 26, formed alongside of the teeth 33. The tooth 29 on said locking and driving unit also rides on said raised surface 40 and locks said unit against turning in the opposite direction during the travel of the segment. As the segment reaches its normal position, a raised portion 41 on the flat segment surface strikes the tooth 29 and gives said locking and driving unit a slight turn, so that tooth 29 will be positively struck by the tooth 31 of the segment on its next depression in the manner described above.

The end teeth 29 and 30 on said locking and driving unit are identical, and as will be seen from tooth 30 at Fig. 3, they extend wider than do the intermediate teeth 33, and the depressions 31 and 39 in the segment where said teeth 29 and 30 are arranged to enter during the downward movement of the segment are cut entirely across the raised surface 40 on said segment, so that in the normal revolution of the locking and driving unit by said downward movement, the parts will not be locked. The locking cam 35 of the aforesaid locking and driving unit is cut away at 42, so that the intermediate shaft 28 may be normally unlocked, so far as the individual locking and driving units are concerned.

- Whenever a numeral key is depressed to operate the computing mechanism, the key first locks the totalizer carriage against movement transversely to the master wheel, 5 by moving a latch 43 to enter a rack 44 on the totalizer carriage. This latch is moved positively into and out of engagement with said totalizer carriage, and for this purpose each locking and driving unit comprises a 10 cam 45, which swings a cam finger 46 outwardly as the unit is turned by its segment, so that said finger rocks a shaft 47 carrying an arm 48 to which said latch 43 is pinned, and moves latch 43 upward into the rack 44. 15 The master wheel then is turned by further revolution of the segment 26. As the segment 26 completes the turning of the locking and driving unit 27, a second cam 49 forming part of said unit strikes a finger 50 also 20 fast on shaft 47, and positively moves said latch 43 downward out of rack 44.
- As the master wheel turns as above described, it turns an idle wheel 20 which in turn drives the computing wheel 23 meshing 25 with the dial wheel 22, as above described.
- Each computing wheel 23 engages a carry-over mechanism which is arranged to turn the adjacent computing wheel higher in denomination one-tenth of a revolution every 30 time its dial wheel passes zero. For this purpose the computing mechanism comprises a series of carry-over wheels 52 (see Figs. 2 and 5) each comprising a gear 51 constantly meshing with its computing wheel 23.
- Each carry-over wheel also comprises (see 35 Figs. 2, 5 and 6) a mutilated gear 53 which is arranged to be struck by a broad tooth 54 on the computing wheel operating this carry-over wheel once in each revolution of said 40 computing wheel. When so struck the carry-over wheel starts to turn and swings an interrupted gear 55 formed as a unit with the carry-over wheel, so that the teeth of said interrupted gear are struck by the teeth 45 56 of a constantly driven wheel 57, which constantly driven wheel completes the cycle of the carry-over mechanism, that is to say, completes the tenth of a revolution of the computing wheel with which the said carry-over wheel meshes.
- Each computing wheel is kept alined by a spring detent roll 59, which roll is arranged to sink into depressions 58 between the interrupted portions of the gear 55 of its carry-over wheel. Thus it arrests the carry-over wheel 52 against overthrow by the constantly driven gear 57; and since the dial wheel is constantly in mesh with the computing wheel, which in turn is constantly in mesh with the carry-over wheel, the detent will hold the dial wheel alined.
- When a numeral key is depressed, the detent controlling the dial wheel then engaged by the master wheel, is moved to an inoperative position, so that the dial wheel may 50 turn freely. For this purpose an extension 62 on the arm carrying the detent 59 carries pivoted thereto a lifter bar 61, which is arranged to be struck and lifted by an extension 60 of the above described latch 43 as 70 said latch rises to lock the totalizer carriage against movement. In this way the dial wheel operated at any moment by the master wheel is free from control of any detent, and the dial wheel is also positively arrested 75 by the master wheel at the proper point, because, as has been pointed out, the locking and driving unit above described always locks or drives positively the mechanism with which it is engaged. As the numeral 80 key completes its downward stroke, the detent 59 again falls into place, and holds its dial wheel. Since the units wheel has no carry-over wheel driving it, a wheel identical with the other carry-over wheels may 85 be arranged to mesh with said wheel, and be controlled by a detent 59 precisely as are the carry-over wheels for the other computing wheels. The lifter bars 61 are held adjacent the rear wall of the totalizer where they 90 will be raised *seriatim* by the extension 60, by means of a rod 61^a which extends across the totalizer and passes through slots in said bars.
- The power assisting wheel 57 above described, is on a shaft 63, which is resiliently journaled so that its teeth in striking the teeth 55, will not be stripped or crushed. Said resilient journals swing on a shaft 64 arranged to drive said assisting wheel by 100 a gear wheel 65 meshing with a gear 65^a which, in turn, meshes with a gear 66 on the shaft 63 of the aforesaid assisting wheel. A spring 67 swings said journals so that said assisting wheel is in position to be struck 105 by the teeth 55 when the carry-over wheel 52 begins to turn. Said assisting wheel is driven by an electric motor 76 through shafts 68, 69 and 70.
- The rotation may be reversed to serve for 110 either addition or subtraction by a reversing clutch between the shafts 69 and 70, comprising a double seizing member 71, slidably splined on said shaft 70, and adapted to engage either of two spur gears 72 loose on said shaft, so that whichever gear 72 is engaged by said seizing member 71, will be locked to said shaft. A spur gear 73 fast on the shaft 69 constantly engages both of said spur gears 72 and so drives the shaft 70 in one direction 115 or the other, according to the position of said seizing member.
- A handle 74 pivoted at 75 is arranged to throw said seizing member into either of the gears 72, and in so doing, a gear for the 120 master wheel reverses simultaneously by throwing gear wheel 75^a slidably splined on shaft 28 to mesh either with a gear 76 fast on the shaft 77 of master wheel 21, or else with an idle wheel 78 meshing with a gear 130

79 fixed on said shaft 77. This enables the whole mechanism to be shifted either for addition or subtraction simultaneously. As shown in Fig. 3, the clutch and the driving gear 75^a are both in their neutral position, so the computing mechanism is disconnected from the keys and power, and the computing mechanism is idle.

The carry-over assisting wheel 57, it will be noted, may be arranged to rotate constantly, so when the totalizer shows a long series of nines, it may happen that some of the carrying over will be done during the motion of the carriage, owing to the fact that the carry-over wheels are operated one after another. In such case the assisting wheel 57 might tend to bind on the carry-over wheels 55 and either delay the carriage, or tend to strip the teeth of said gears 55. In order to prevent any such trouble, the tooth bearing surface 80 of said wheel 57 is divided into two portions, one of which, 81, is fixed on the shaft 63 of said wheel, while the other portion, 82, is slidably splined on said shaft, so that it may slide to the left if the carriage tends to drag it in that direction, and it is returned from any such dragging by means of a spring 83. The portion 81 of said toothed surface fixed to said shaft 63 is so aligned with reference to the master wheel, that its righthand edge will engage the carry-over wheel operated by the dial wheel engaged by the master wheel, and said portion extends for a slight distance to the left where it ends in a toothed portion somewhat resembling a crown gear. The slideable portion 82 has similar crown teeth on it, and the spring 83 normally holds these portions closed together. If, however, the portion 82 is dragged along as above described, the crown-like teeth 84 will prevent any continuous open gap in said assisting wheel from being opposite any carry-over wheel, so that said assisting wheel is certain to complete the turning of every carry-over wheel.

It will be noted that when a numeral key is depressed, it carries along the segment 26, but no other parts of the computing mechanism are moved until about one-third of the down-stroke of the key has been completed, then a tooth 48 on the segment strikes a tooth 30 of the locking and driving member, and starts that member, and after said member has obtained some momentum, then the tooth 37 which actually drives the master wheel begins to turn said master wheel. In the meantime after said locking and driving member has attained its speed, the latch 43 has moved upward and lifted the detent 59 out of the carry-over wheel. Thus it will be seen that the various parts attain their movement one after another, so that there is no sudden load brought on to the keys. If any carrying over is done, the assisting

wheel 57 will take care of that by itself, so that carrying over brings no extra load on the numeral keys.

Where, as in the present disclosure, the computing mechanism is used in combination with an Underwood typewriter, it will be observed that the type has attained its momentum before the computing mechanism proper begins to operate, so that in this combination, the touch of the keys will be exceedingly light and uniform throughout the stroke.

The sliding member 80 of the carry-over assisting wheel 57 may be limited in its throw by a pin 85; and the resilient journals 80 of the shaft 63 may be limited in their throw by an adjustable screw 86.

Variations may be resorted to within the scope of the invention, and portions of the improvements may be used without others.

Having thus described my invention, I claim:

1. In a computing machine, the combination with computing wheels and numeral keys, of a carry-over wheel for each computing wheel, each carry-over wheel constantly in mesh with a computing wheel, a spring detent for each computing wheel and effective on its carry-over wheel, means for driving said computing wheels by said keys, and means, brought into action by any key at the beginning of its movement, for removing the detent from the computing wheel which is to be driven, whereby the key is relieved of the burden of said detent while driving said computing wheel.

2. In a computing machine, the combination with computing wheels and numeral keys, of a master wheel operating *seriatim* on said computing wheels, a carry-over wheel for each computing wheel, each carry-over wheel constantly in mesh with its computing wheel, a spring detent holding each computing wheel aligned and effective on its carry-over wheel, means for driving said master wheel by said keys, means for holding said master wheel positively locked when not driven, and means, brought into action by a key at the beginning of its movement, for unlocking the master wheel and for removing the detent from the computing wheel which is to be driven.

3. In a computing machine, the combination with computing wheels, of a master wheel traveling relatively to them, means including a detent associated with each computing wheel for holding it aligned, numeral keys arranged to turn said master wheel to turn said computing wheels *seriatim*, and means for locking said computing wheels and master wheel against relative travel, and for releasing from the control of its detent, by the depression of a numeral key, the computing wheel which is being operated by the master wheel.

4. In a computing machine, the combination with computing wheels and numeral keys, of means for driving said wheels from said keys *seriatim*, a detent associated with each computing wheel for normally holding it alined, means operated by any key for releasing from the control of its detent the wheel which is about to be driven from said key while leaving the remaining detents controlling their respective wheels of higher orders, a carry-over wheel for each computing wheel, a power-driven wheel for turning each carry-over wheel when started by a computing wheel, said detents preventing overthrow of the computing wheels in carrying from lower to higher orders, and means for locking at the completion of its rotating movement the computing wheel that is rotated by a key.
- 20 5. In a computing machine, the combination with numeral keys and a master wheel, of a traveling carriage comprising computing wheels and a carry-over mechanism, a source of power for driving said carry-over mechanism, and a fixedly journaled shaft carrying a slideable wheel driven from said source of power and arranged to travel momentarily with said carry-over mechanism to drive it.
- 30 6. In a computing machine, the combination with numeral keys and a master wheel, of a traveling carriage comprising computing wheels and a carry-over mechanism, a source of power for driving said carry-over mechanism, a fixedly journaled shaft carrying a gear wheel slidably splined on it, means for driving said shaft from said source of power, resilient means holding said shaft so that it will engage with said carry-over mechanism to drive it, and a spring returning said wheel from any point to which it may slide with said carry-over mechanism.
- 45 7. In a computing machine, the combination with numeral keys and a master wheel, of a traveling carriage comprising computing wheels and a carry-over mechanism, a source of power for driving said carry-over mechanism, a fixedly journaled shaft comprising a gear fast to it arranged to drive part of said carry-over mechanism, and a slideable gear splined on said shaft arranged to drive another portion of said carry-over mechanism and travel with it momentarily.
- 55 8. In a computing machine, the combination with numeral keys and a master wheel, of a traveling carriage comprising computing wheels and a carry-over mechanism, a source of power for driving said carry-over mechanism, a fixedly journaled shaft comprising a gear fast to it arranged to drive part of said carry-over mechanism, a slideable gear splined on said shaft arranged to always overlap said first gear during the revolution of said shaft arranged to drive another portion of said carry-over mechanism, and a spring returning said slideable gear against said fixed gear.
- 90 9. In a computing machine, the combination with numeral keys and a master wheel, of a traveling carriage comprising computing wheels and a carry-over mechanism, a source of power for driving said carry-over mechanism, a fixedly journaled shaft comprising a gear fast to it arranged to drive part of said carry-over mechanism, a slideable gear splined on said shaft comprising crown extensions arranged to overlap crown extensions on said fixed gear, so that said slideable gear drives another portion of said carry-over mechanism, and a spring holding said slideable gear against said fixed gear.
- 100 10. In a computing machine, the combination with computing wheels and numeral keys, of a master wheel driven by said keys to turn said computing wheels *seriatim*, carry-over wheels controlled by said computing wheels, a source of power for driving said carry-over wheels, a clutch intermediate said keys and master wheel for reversing said master wheel to cause it to either add or subtract, a similar clutch intermediate said source of power and carry-over wheels, and means for simultaneously operating said clutches.
- 110 11. In a combined typewriting and computing machine, the combination with numeral keys and computing wheels, of a master wheel operating *seriatim* on said computing wheels, means including a detent associated with each computing wheel to aline the same, a lock arranged to prevent transverse movement between the master wheel and the computing wheels while the master wheel is being operated, and an extension on said lock for moving to inoperative position the detent which controls the computing wheel then operated.
- 120 12. In a computing machine, the combination with numeral keys, computing wheels and a master wheel for engaging said computing wheels *seriatim*, of carry-over wheels, a detent movable independently of its carry-over wheel and normally holding each computing wheel through its carry-over wheel, means for turning said master wheel controlled by the operation of said keys, and means controlled by the keys for releasing the detent holding the computing wheel engaged by the master wheel before the master wheel begins to turn.
- 130 13. In a computing machine, the combination with numeral keys, computing wheels, and a traveling carriage, of a master wheel for engaging said computing wheels *seriatim* to an extent determined by said keys, carry-over wheels, a detent movable independently of its carry-over wheel for holding each computing wheel through its carry-over

wheel, and a single member under the control of said keys before they turn the master wheel to lock said carriage and release the detent from the computing wheel engaged by the master wheel.

14. In a computing machine, the combination with a key-driven rotating member always rotating in the same direction, of computing wheels, carry-over wheels, a master wheel turned by said keys to engage said computing wheels *seriatim* as determined by said rotating member, a spring detent for holding each computing wheel, power means for turning the computing wheels in carrying over against their detents, a carriage on which the computing wheels are mounted, and a single member controlled by said rotating member for releasing the detent of the computing wheel engaged by the master wheel, and for locking said carriage before the master wheel starts to rotate.

15. In a computing machine, the combination with a key-driven rotating member always rotating in the same direction, of computing wheels, carry-over wheels, a master wheel turned by said keys to engage said computing wheels *seriatim* as determined by said rotating member, a spring detent for holding each computing wheel, power means for turning the computing wheels in carrying, a carriage on which the computing wheels are mounted, a single member controlled by said rotating member for releasing the detent of the computing wheel engaged by the master wheel, and for locking said carriage before the master wheel starts to rotate, and means for positively unlocking said carriage by said rotating member.

16. In a computing machine, the combination with numeral keys and computing wheels, of means for determining by said keys how far said computing wheels shall be turned, a master wheel for so turning them, carry-over wheels, a detent for each computing wheel normally holding it and effective on its carry-over wheel, means moving independently of the carry-over wheels for releasing the detent holding the computing wheel engaged by the master wheel before the master wheel begins to turn, and means for locking the master wheel and the computing wheel against transverse relative movement.

17. In a computing machine, the combination with numeral keys and computing wheels, of a master wheel for turning said computing wheels, carry-over wheels, a traveling carriage for causing *seriatim* engagement of said master wheel and said computing wheels, a detent for holding each computing wheel and effective on its carry-over wheel, means moving independently of the carry-over wheels for releasing the detent holding the computing wheel engaged by the master wheel, means for positively

rotating and positively arresting said master wheel while it is free from said detent, and means for positively releasing said detent to return to its effective position after the master wheel has been arrested.

18. In a computing machine, the combination with computing wheels, of a spring detent holding each computing wheel, a master wheel for turning said computing wheels *seriatim*, carry-over wheels, power means for driving said carry-over wheels adapted to overcome said detents, and means for moving the detent holding a computing wheel to ineffective position while said wheel is engaged by the master wheel but before said master wheel begins to turn.

19. In a combined typewriting and computing machine, the combination with numeral keys and computing wheels, of a traveling carriage, a master wheel, carry-over wheels each constantly engaged with one computing wheel and arranged to be controlled by another, a detent for each carry-over wheel normally holding its computing wheel, a power-driven member arranged to complete the turning of the carry-over wheels against the detents when initially turned by the computing wheels controlling them, means for releasing the detent holding the computing wheel engaged by the master wheel, means for positively arresting the master wheel when it is completely turned, and means permitting said detent to be restored to effective position when said master wheel has been so arrested.

20. In a computing machine, the combination with computing wheels and a master wheel for turning them *seriatim*, of numeral keys, connections whereby said master wheel is driven by the depression of a key to an extent dependent on the key depressed, a carry-over wheel for each computing wheel, and a power-driven member adjacent only the carry-over wheels above the master wheel in denomination for turning said carry-over wheels.

21. In a combined typewriting and computing machine, the combination with numeral keys and computing wheels, of a master wheel for turning said computing wheels *seriatim*, a series of locking and driving members, one for each numeral key, means whereby each member alternately locks, drives and locks said master wheel, carry-over wheels, a power driven device for driving said carry-over wheels, a detent normally holding each computing wheel, and means for moving said detent to ineffective position by the initial movement of any locking and driving member.

22. In a combined typewriting and computing machine, the combination with numeral keys and computing wheels, of a master wheel for turning said computing wheels *seriatim*, a series of locking and driving

members, one for each numeral key, means whereby each member alternately locks, drives and locks the master wheel, carry-over wheels, a power driven device for driving said carry-over wheels, a detent normally holding each computing wheel, means for moving said detent to ineffective position by the initial movement of any locking and driving member, a traveling carriage for determining which of said computing wheels said master wheel shall engage, and means for locking said carriage when each locking and driving member begins to turn.

23. In a combined typewriting and computing machine, the combination with numeral keys and computing wheels, of a master wheel for turning said computing

wheels, a series of locking and driving members, one for each numeral key and always turning in the same direction, a traveling carriage for determining how said computing wheels shall engage said master wheel, means including a detent associated with each computing wheel and normally effective to hold the same, and unitary means operated by each locking and driving member for locking said carriage and releasing said detent by the initial depression of a numeral key.

WALTER WRIGHT.
